FOLDABLE SUPPORTING POST FOR X-RAY EQUIPMENT AND THE LIKE

Elias Edward Resk, 442 E. 20th St., New York 9, N.Y.

Filed Feb. 15, 1963, Ser. No. 73,585

Term of patent 14 years

(Cl. D83—1)

FIG. 1

FIG. 2

FIG. 3

FIG. 1 is a front perspective of a foldable supporting post for X-ray equipment and the like embodying my new design;

FIG. 2 is a perspective taken from the right of FIG. 1; and

FIG. 3 is a top plan view thereof.

I claim:

The ornamental design for a foldable supporting post for X-ray equipment and the like, substantially as shown.
